United States Patent Office

Des. 187,991
Patented May 24, 1960

187,991

PIGGY BANK

Abraham J. Weiner, 1426 Walton Ave., Bronx, N.Y.

Filed Oct. 2, 1959, Ser. No. 57,772

Term of patent 14 years

(Cl. D34—11)

Fig. 1 is a front elevational view of a piggy bank showing my new design.

Fig. 2 is a side elevational view thereof.

Fig. 3 is a rear elevational view of the same.

Fig. 4 is a top plan view of the new design.

I claim:

The ornamental design for a piggy bank, substantially as shown.
